Attorney, Agent, or Firm—Jay H. Maioli***[57] CLAIM**

The ornamental design for a portable global positioning system receiver, as shown and described.

DESCRIPTION

FIG. 1 is a top, front and right-side perspective view of a portable global positioning system receiver showing my new design;

FIG. 2 is a top, front and right-side perspective view thereof, shown with antenna in the rotated position;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

FIG. 1

FIG.2

FIG. 3
